CORE DRILL

Application filed June 19, 1928. Serial No. 286,692.

My invention relates to core drills of the general character operated by cable tool systems in the well drilling art for obtaining a sample core of the ground formation penetrated by the drill when in operation.

It is a purpose of my invention to provide a core drill characterized by its capability of positively maintaining the core barrel against upward displacement from the ground formation penetrated by the core barrel so as to prevent distortion of the core being obtained and dislodging thereof from the core barrel as the drilling proceeds; its capability of aiding the upward feed of the core in the barrel as the latter penetrates the formation; its capability of preventing packing of the core in the barrel with the resultant blocking of the barrel by the core; its capability of preventing bending of, or other damage to the barrel by obstructions in the hole when lowering the drill into the hole; and its capability of being readily withdrawn from the hole even though the walls of the latter should crumble or cave in, to the end that the drilling operation will be greatly facilitated and a true and accurate sample core of the formation penetrated by the drill, obtained in, and readily removed intact from the core barrel when the drill is withdrawn from the hole.

I will describe only one form of core drill embodying my invention and will then point out the novel features in claims.

In the accompanying drawings.

Fig. 1 is a view showing in vertical longitudinal section one form of core drill embodying my invention, and illustrating the positions occupied by the moving parts of the drill when the latter is to be lowered into a bore hole;

Fig. 2 is a view similar to Fig. 1 and showing the drill lowered into a bore hole and commencing the downstroke;

Fig. 3 is a view similar to Fig. 1 and illus-

trating the downstroke of the drill as being partially completed;

Fig. 4 is a view similar to Fig. 1 and illustrating the downstroke of the drill as fully completed;

Fig. 5 is an enlarged detail sectional view of a valve structure embodied in the drill; and

Fig. 6 is a sectional view taken on the line 6—6 of Fig. 5.

Referring specifically to the drawings in which similar reference characters designate similar parts in each of the several views, my invention in its present embodiment comprises a metal body B of cylindrical form, having an axial bore 10 extending longitudinally therethrough, which is enlarged at its lower end and threaded to receive a threaded pin 11 of a conventional form of drill bit D so as to detachably secure the bit to the body. The bit D is provided with an axial bore 12 forming a continuation of the bore 10 of the body, and the bore 12 is reduced in diameter at the lower end of the bit as indicated at 13, to provide an annular shoulder 14.

The upper end of the bore 10 of the body B is also enlarged and threaded to receive a threaded projection 15 on one end of a coupling pin 16, while a second threaded projection 17 on the other end of the pin is adapted to be screwed into a conventional form of drill stem S so as to secure the body B to the stem for reciprocation by conventional mechanism (not shown) in a bore hole to effect cutting and penetration of the formation in the hole by the bit D as is well known in the art and will be understood.

Within the bores 10 and 12 is mounted for sliding movement relatively to the body B a core barrel C having its lower end provided with a conventional form of core shoe 18. In the present instance the upper end of the core barrel is provided with a valve structure comprising an open ended tubular member 19 of the same diameter as the core barrel, the

member 19 forming a continuation of the upper end of the core barrel and being secured thereto by a coupling collar 20 which also serves to clamp a perforated disk 21 between the member and core barrel.

The member 19 is provided with a circular series of slots which constitute ports 22 controlled by a valve designated generally at V and comprising an inner sleeve 23 extending freely into the upper end of the member 19, and an outer sleeve 24 freely surrounding the member 19. The upper end of the sleeve 23 is threaded internally to receive a reduced, threaded projection 25 formed on a cap 26 having a peripheral flange 27 threaded onto the sleeve 24 as indicated at 28, to the end that the sleeves and cap will be secured together to form a single unit.

The valve V is normally urged upwardly 20 to the extreme position shown in Fig. 5 wherein its sleeves 23 and 24 open the ports 22, by a coil spring 29 loosely fitting within the sleeve 24 and abutting the disk 21 and the underside of the projection 25 of the cap 26.

25 The uppermost position to which the valve V can be moved under the action of the spring 29 is definitely limited by means of external and internal flanges 30 and 31 formed on the lower ends of the sleeves 23 and 24 30 respectively, which are adapted to abut internal and external flanges 32 and 33 respectively, formed on the upper end of the tubular member 19. The valve V is adapted to be moved downwardly to the extreme position 35 shown in Figs. 1, 3 and 4 wherein its sleeves 23 and 24 cooperate to close the ports 22, in a manner to be hereinafter fully described.

The core barrel C is adapted to be driven into the formation at the bottom of a bore 40 hole and maintained against upward displacement from the formation during reciprocation of the body B, by means of an operative connection between the body B and core barrel, which in the present instance comprises 45 a coil spring 34 loosely fitting the bore 10 and resting upon the cap 26; a weight 35 of cylindrical form, also loosely fitting the bore 10 and having at one end a reduced extension 36 entering the spring 34 to prevent relative 50 lateral displacement of the weight and spring; and a second coil spring 37 of greater strength than the spring 34 and loosely fitting the bore 10. The spring 37 normally rests upon the weight 35 and receives a reduced 55 tension 38 formed on the opposite end of the weight so that relative lateral displacement of the second spring and weight is prevented.

It will be noted that a retaining member 60 in the form of a collar 39 is threaded into the lower end of the bore 10, and that the internal diameter of the member is such as to freely pass the core barrel C and its valve V when it is desired to withdraw the barrel from the body B after removal of the bit D, yet prevents passage of the spring 34 so that the lat-

ter as well as the weight 35 and second spring 37 are prevented from dropping out of the barrel into the bore hole or possibly injuring workmen.

Furthermore, the core barrel is adapted to 70 be releasably held in the retracted position in the body B, as is shown in Fig. 1, by a shearable means, in the present instance comprising a pair of pins 40 of soft metal which are threaded into lugs 41 formed at diametrically opposed points on the underside of the bit D adjacent its bore 12, and adapted to be tightly screwed against the core barrel, so that the core barrel will be held in retracted position with only the lower extremity of the core barrel and core shoe thereon projecting from the bit D. The danger of bending or otherwise damaging the core barrel when lowering the drill into the bore hole is thus prevented. However, when the core shoe 18 80 strikes the formation at the bottom of the bore hole, the weight of the body B and the drilling string imposed on the pins 40, will cause the latter to shear off so that the core barrel will be free to move to extended position with respect to the body B.

The operation of the core drill is as follows:

Assuming that the drill has been lowered into the bore hole and that the pins 40 have 90 been sheared off, the drill will be submerged in the flushing liquid in the hole and the liquid will be free to enter the bore 10 of the body B through pressure relief ducts 42 formed in the side wall of the body, and to 100 enter the core barrel through the ports 22.

Reciprocation of the body B by the usual mechanism (not shown) is initiated, and during the downstroke of the body from the position shown in Fig. 2 flushing liquid in the bore 10 is ejected therefrom through the ducts 42. When the projection 15 of the coupling pin 16, which closes the upper end of the body, strikes the spring 37, the valve V is moved downwardly through the medium of the weight 35 and spring 34, to cause flushing liquid in the core barrel to be ejected therefrom into the bore 10, through the ports 22 and thence out of the bore 10 through the ducts 42. Continued downward movement of the body B moves the valve V to its lowermost extreme position shown in Fig. 3 to thus close the ports 22, after which the springs 34 and 37 are compressed as shown in Fig. 4 to transmit to the core barrel, a cushioned blow operating to drive the barrel into the formation at the bottom of the bore hole as the bit D cuts into the formation. A sample core of the formation being penetrated by the bit D is thus forced up into the core barrel, and to prevent packing of the barrel with the consequent blocking up of the barrel by the core, the barrel is tapered internally to increase in diameter upwardly of the barrel as indicated at 43.

125
130

When the return or upstroke of the body B is initiated, the springs 34 and 37 first expand, and although the spring 34, in its rebounding action, tends to violently project the weight 35 upwardly against its normal function of exerting a downward force on the barrel through the medium of the spring 34 and valve V, the spring 37 being of greater strength than the spring 34 resists and overcomes the rebounding action of the latter spring to such extent that the weight is held down in engagement with the spring 34 so as to continue to exert its downward force upon the barrel. The barrel is thus held down 15 against upward displacement from the formation, so that distortion of the core being formed in the barrel or dislodging of the core from the barrel, is positively prevented, to the end that a true and accurate sample of the 20 formation being penetrated by the drill, will be obtained.

Upon continued upward movement of the body, and when sufficient movement of the latter has been effected to permit the springs 25 34 and 37 to fully expand, the spring 29 operates under its normal urging action to move the valve V upwardly and suddenly open the ports 22. As the pressure relief ducts 42 will not permit a sufficient quantity 30 of flushing liquid to enter and immediately fill the bore 10 of the body and the space in the core barrel above the core therein, as the upstroke of the body progresses, a partial vacuum is produced in the bore and barrel 35 during the upstroke of the body so as to tend to suck or draw the core upwardly in the barrel. Sticking of the core in the barrel is thus prevented and the upward feed of the core greatly facilitated.

It will be appreciated that the operations 40 of the springs 34 and 37, weight 35, and valve V, as a result of the reciprocations of the body B, occur very rapidly as the body is reciprocated at a speed of approximately 45 thirty strokes per minute so that the suction is induced in the barrel very quickly to act with maximum effectiveness on the core in the barrel. Furthermore, it will be noted that the strength of the spring 29 is sufficient 50 to raise the valve V, spring 34, weight 35, and spring 37 so as to maintain the valve open when the projection 15 is clear of the latter spring.

It will be clear that on the downstroke of 55 the body B, the springs 34 and 37 effectively prevent a sharp blow from being delivered against the core barrel so that bending or kinking of the barrel is prevented, and the barrel driven down into the formation without undue stress thereupon, as well as positively maintained at all times during the drilling operation against upward displacement from the formation so that a true and accurate sample core of the formation will 60 be recovered.

When the barrel has been driven into the formation sufficiently to obtain the desired length of core, the body is raised from the bore hole, and during the upward movement of the body, the shoulder 14 in the bit D strikes the sleeve 24 of the valve V and thus withdraws the core barrel from the formation and causes the barrel to remain suspended from the body and raised therewith from the hole.

The body B is tapered exteriorly so as to increase in diameter upwardly, as is indicated at 44, which tapered form greatly facilitates withdrawal of the drill from the bore hole should the walls of the latter have crumpled or caved in and thus tend to freeze the body in the hole.

Although I have herein shown and described only one form of core drill embodying my invention, it is to be understood that 85 various changes and modifications may be made therein without departing from the spirit of the invention and the spirit and scope of the appended claims.

I claim:

1. A core drill comprising a bit carrying body adapted to be connected to a drill stem for reciprocation thereby in a bore hole, a core barrel mounted for movement in the body and adapted to penetrate the formation in the bottom of the bore hole, means operable by the body during the downstroke of the latter, to drive the core barrel into the formation and thereby obtain a sample core of the formation, and means for creating a partial vacuum in the barrel above the core therein so as to tend to suck the core upwardly in the barrel.

2. A core drill comprising a bit carrying body adapted to be connected to a drill stem for reciprocation thereby in a bore hole, a core barrel mounted for movement in the body and adapted to penetrate the formation in the bottom of the bore hole, means operable by the body during the downstroke of the latter, to drive the core barrel into the formation and thereby obtain a sample core of the formation, and means operable upon one stroke of the body to eject from the barrel, flushing fluid therein above the core, and operable upon the other stroke of the body to induce suction in the barrel above the core so as to tend to draw the latter upwardly in the barrel.

3. A core drill comprising a bit carrying body adapted to be connected to a drill stem for reciprocation thereby in a bore hole, a core barrel mounted for movement in the body and adapted to penetrate the formation in the bottom of the bore hole, means operable by the body during the downstroke of the latter, to drive the core barrel into the formation and thereby obtain a sample core of the formation, and means operable upon one stroke of the body to eject from the bar-

- rel, flushing fluid therein above the core, and operable upon the other stroke of the body to induce suction in the barrel above the core so as to tend to draw the latter upwardly in 5 the barrel, said last means comprising ports in the core barrel, and a valve for controlling the ports, normally urged to one position to open the ports and movable by the first means to a second position wherein 10 it closes the ports.
4. A core barrel having ports, and a valve mounted for movement on the core barrel to open or close the ports according as the valve occupies one position or another, and means 15 for normally urging the valve to the position wherein the ports are open.
5. A core barrel having ports, and a valve comprising an inverted cup shaped element closing the upper end of the core barrel and 20 slidably mounted on the latter to open or close the ports, according as the element occupies one extreme position or another, and means for urging the element to one extreme position.
- 25 6. A core drill comprising a bit carrying body adapted to be connected to a drill stem for reciprocation thereby in a bore hole, a core barrel mounted for movement in the body and adapted to penetrate the formation 30 in the bottom of the bore hole, and a yieldable operative connection between the body and core barrel by which the latter is caused to be driven into the formation to obtain a sample core thereof, upon the downstroke of the body, 35 and is maintained against displacement from the formation upon the upstroke of the body, whereby distortion of the core will be prevented and a true and accurate sample of the formation being penetrated, obtained, said 40 operative connection comprising a spring in the body engaging the upper end of the barrel, a weight resting upon the spring and adapted to exert pressure downwardly upon the barrel through the medium of the spring, 45 and a second spring in the body, resting upon the weight and adapted to be struck and compressed by the body during the downstroke thereof, to transmit the movement of the body to the barrel through the medium of the 50 weight and the first spring, said second spring being of greater strength than the first spring and operable during the upstroke of the body to prevent sudden rebounding of the first spring so that the weight will constantly act 55 to hold the core barrel down and against displacement from the formation.
7. A core drill comprising a body having a bit on its lower end, the body and bit being provided with a bore extending longitudinally and opening to the lower end of the bit, 60 a core barrel slidably mounted in the bore, a coil spring in the bore resting upon the upper end of the core barrel, a weight in the bore resting upon the spring, and a second 65 spring in the bore resting upon the weight, the second spring being of different strength than the first spring.
8. A core drill comprising a body having a bit on its lower end, the body and bit being provided with a bore extending longitudinally and opening to the lower end of the bit, a core barrel slidably mounted in the bore, a coil spring in the bore resting upon the upper end of the core barrel, a weight in the bore resting upon the spring, a second spring in the bore resting upon the weight, and a retaining member removably fitted in the bore of the body, for preventing dropping of the 70 springs and weight from the bore when the bit is removed from the body and the barrel withdrawn from the bore.
9. A core drill comprising a bit body, adapted for connection to a drill stem for reciprocation thereby and having a bore extending longitudinally therein, a core barrel slidably mounted in the bore of the body and having ports, a valve comprising a sleeve slidably mounted on the upper extremity of the core barrel for opening or closing said 75 ports according as the sleeve occupies one extreme position or the other, means for normally urging the sleeve to the extreme position in which the ports will be open, and a yieldable operative connection in the bore, for moving the valve to its closed position and driving the core barrel into ground formation during the downstroke of the body.
10. A core drill comprising a body having a bore, a core barrel slidably in the bore, a weight in the bore, a spring in the bore between the core barrel and weight, and a second spring in the bore between the weight and body, the springs being of different strengths.
11. A core drill comprising a body having a bore, a core barrel slidable in the bore, a weight in the bore, a spring in the bore between the core barrel and weight, and a second spring in the bore between the weight and body, and being of greater strength than the first spring.
12. A core drill comprising a bit body, a core barrel mounted for movement in the body and having a port, a valve controlling the port and normally urged to a position to open the port, and means for moving the valve to a second position to close the port during the downstroke of the body.
13. A core drill comprising a bit body, a core barrel mounted for movement in the body and having a port, a valve controlling the port and normally urged to a position to open the port, and means for moving the valve to a second position to close the port during the downstroke of the body, and driving the core barrel into ground formation during the 100 downstroke of the body.
14. A core drill comprising a bit body, a core barrel slidably in the body for driving by the body into ground formation during the downstroke of the body, and means for 105
- 110
- 115
- 120
- 125

ejecting flushing fluid from the core barrel above a core therein during one stroke of the body.

15. A core drill comprising a bit body, a core barrel slideable in the body for driving by the body into ground formation during the downstroke of the body, and means for inducing suction in the core barrel above a core therein during one stroke of the body so as to tend to draw the core upwardly in the barrel.

Signed at Los Angeles, in the county of Los Angeles, and State of California this 2d day of June A. D. 1928.
